VARNISH APPLICATOR MECHANISM FOR
SHEET VARNISHERS

Elmer W. Belluche and Frank R. Belluche,
Racine, Wis., assignors to The Christensen Ma-
chine Company, Racine, Wis., a corporation of
Wisconsin

Original application November 30, 1942, Serial
No. 467,370. Divided and this application Sep-
tember 21, 1946, Serial No. 698,418

14 Claims. (Cl. 91—51)

1

This invention relates to the printing art, and is particularly directed to varnishing machines, being a division of the co-pending application, Serial No. 467,370, filed November 30, 1942, now Patent No. 2,424,732.

Broadly, it is an object of this invention to provide means for protecting the varnish cylinder of varnishers against receiving a coating of varnish in the event a sheet is not fed thereto, which occurs when an imperfect sheet is presented at the front guides of the machine.

Inasmuch as this invention contemplates allowing the machine to continue to operate notwithstanding the feeding of a defective sheet, as fully brought out in the aforesaid application, now Patent No. 2,424,732, a sheet already on the impression or varnish cylinder is delivered in the usual way.

Hence, the impression or varnish cylinder, at least for one cycle, runs naked. To prevent an impression on the naked cylinder the present invention has as another of its objects to provide means for automatically opening the printing or varnishing couple by effecting retraction of the plate cylinders or the varnishing roll away from the impression cylinder concomitantly with the rejection of the imperfect sheet.

In this respect it is more specifically an object of this invention to provide a releasable latch mechanism for holding the varnish roll or plate cylinders in their operative positions, which latch mechanism is adapted to be tripped in consequence to the actuation of the trip mechanism in response to the presentation of an imperfect sheet at the front guide.

Whenever a varnisher is stopped there is always the possibility that the varnish on the applicator rolls and in the fountain will set. Hence, it is desirable to keep the applicator rolls running. In varnishers heretofore in use no provision was made for this other than to move the varnish roll away from the impression cylinder without disconnecting it from the drive of the machine so that the machine could be run empty, i. e. without having sheets pass through.

The present invention, however, contemplates the provision of simple means for running the varnish applicator rolls to agitate the liquid varnish in the fountain and prevent setting thereof without necessitating running the entire machine by providing an independent drive for the applicator rolls adapted to be automatically rendered operative upon racking back or retracting the entire varnish applicator assembly.

With a view toward providing maximum con-

2

venience the present invention also has as one of its objects, the provision of an improved varnish applicator assembly so designed and constructed that access to all parts thereof is easily had.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

20 Figure 1 is a side view of a varnishing machine diagrammatically illustrating the elements with which this invention is concerned;

Figure 2 is a feed side view of a varnishing machine embodying this invention and showing the parts diagrammatically illustrated in Figure 1;

25 Figure 3 is a perspective view of the levers and linkage through which response of the detector finger upon presentation of an imperfect sheet at the front guide of the machine acts to prevent transfer of the defective sheet to the impression cylinder and simultaneously retracts the varnish applying roll;

30 Figure 4 is a side view of the varnish applicator assembly illustrating the same in its retracted position with the varnish applying roll spaced from the impression or varnish cylinder;

Figure 5 is a detail perspective view of the adjusting bushing and screw used to adjust the position of the varnish roll with respect to the gauge 35 roll;

Figure 6 is a cross sectional view through the varnish applicator assembly, illustrating the parts in their operative positions;

40 Figure 7 is a cross sectional view similar to Figure 6 but showing the varnish applicator assembly moved out and the varnish roll swung back; and

Figure 8 is a gear side view of the machine illustrating particularly the varnish applicator assembly moved out and being driven by its own independent motor.

Referring now particularly to the accompanying drawings, in which like numerals indicate like parts, the numeral 5 designates the impression or varnish cylinder on which the sheets are

carried in their passage past a varnish applicator, including a varnish roll 6.

The sheets are fed singly to the varnish cylinder by a feed cylinder 7. Both these cylinders have the usual grippers and at their point of tangency, the sheets are transferred from the feed cylinder to the varnish cylinder through suitable manipulation of the grippers.

A feeder of any suitable design presents the sheets S to the front guide 8 of the machine, which is located above the feed cylinder. If the sheet is perfect it is transferred to the impression cylinder and thereby carried past the varnish roll to be presented to the gripper bars 9 of an endless chain conveyor 10, which carries the varnish sheets through a drying chamber, not shown.

If the sheet is defective, as when a corner portion thereof is turned over a detector finger 11 at the front guide is allowed to remain in its normal position whereupon the functioning of the trip mechanism controlled by the detector finger actuates mechanism to be hereinafter described, by which the grippers on the feed and varnish cylinders are left closed as they pass their transfer point so that the defective sheet which has been taken by the feed cylinder is not transferred to the varnish cylinder but is carried around to a discharge point and dropped into a receptacle 12 adapted to hold the discard pile.

The response of the trip mechanism to prevent transfer of the sheet to the impression or varnish cylinder is accompanied by retraction of the varnish roll away from the varnish cylinder to preclude the application of varnish onto the naked cylinder, for as noted hereinbefore, the rejection of the imperfect sheet does not entail stopping the machine. Instead the machine continues to operate and a sheet on the varnish cylinder is delivered therefrom in the usual way so that the varnish cylinder runs naked until the next proper sheet is transferred thereto by the feed cylinder.

As is customary in printing machines, the feed and varnish cylinders are supported by side frames 13, the feed cylinder being mounted on a shaft 14 and the impression or varnish cylinder on a shaft 15.

The grippers (not shown) of the feed and varnish cylinders may be of any suitable form and need not be specifically defined except to point out that the opening of the grippers at the transfer point where the sheet is transferred from the feed cylinder to the varnish cylinder is controlled by retractile cams 18 and 19.

These cams are normally held in their operative positions by retractile supports in the form of bell crank levers 20 and 21, respectively.

When the cams are in their operative positions, the cam following rollers of the grippers riding onto and over the cams open the grippers at the proper time to effect transfer of the sheet, but when the cams are permitted to swing to their inoperative positions, as a result of retraction of the supports 20 and 21, the grippers remain closed. Thus a defective sheet that enters the machine and is picked up by the grippers on the feed cylinder, if not transferred to the impression cylinder is carried to the discharge point where it is released to pass down to a discard pile.

The cam supporting bell crank levers 20 and 21 are held in their operative positions by a linkage restrained against movement to a releasing position by a latch indicated generally by the number 22. The linkage by which the cam supports are held up comprises a lever 23 fixed to a

shaft 24 which is journaled in the adjacent side frame of the machine, the lever 23 being inside the frame.

Links 25 and 26 connect the outer end of the lever 23 with the cam supporting levers 20 and 21 respectively so that as long as the lever 23 is held in its normal raised position defined by an adjustable stop 27, the cam supports hold the cams in their proper operative positions. Assurance that the lever 23 will remain in its normal position defined by the stop 27 is provided by a tension spring 28 which pulls down on the lever. It is to be observed that adjustment of the stop 27 sets the location of the cams 18 and 19.

A horizontal bar 29 connecting the lever 23 with the latch releasably holds the lever in its normal position. This bar 29 has one end thereof connected to an arm of the lever 23 and its other end is connected to a lever 30 medially pivoted on a fixed stub shaft 31. A compression spring 32 acting against the lever 30 yieldingly urges the same in a counterclockwise direction (in Figure 3) and tends to push the horizontal bar 29 to the left. Such leftward shifting of the bar 29 would release the gripper opening cams for gravitational descent to inoperative positions, but as noted hereinbefore the latch 22 restrains the shifting of the bar.

The latch 22 comprises a notch 33 in the bar 29 and a flange 34 carried by a pin 35 and engaging in the notch. The pin 35 is secured to a lever 36 which is pivoted as at 37 upon a fixed support and these parts are so arranged that clockwise rotation of the lever 36 (Figure 3) about its pivotal support is required to disengage the latch 22. A tension spring (not shown) yieldingly restrains such clockwise rotation of the lever 36, but when a defective sheet is presented at the front guides of the machine, the lever 36 is rocked about its pivotal support in a clockwise direction to release the latch 22 and allow the cams to swing to their inoperative positions.

To so actuate the lever 36 in response to the presentation of a defective sheet at the front guides, a lever arm 38 fixed to a shaft 39 carries a finger 40 at its lower outer end in line with a roller on the end of the lever 36. An adjustable stop (not shown) defines the normal position of the lever arm 38 from which the arm swings outwardly in a counterclockwise direction to rock the lever 36 upon oscillation of the shaft 39 in a counterclockwise direction.

Such oscillation of the shaft 39 is brought about in the following manner: the shaft 39 which extends across the entire width of the machine has a plurality of levers 42 fixed thereto which in the normal position of the shaft 39 extend substantially horizontally toward the direction from which the sheets are fed. The levers 42 are in exact alignment and the number employed depends upon the width of the sheets. At least two are employed and they are adjusted along the length of the shaft 39 to be near the sides of the sheet.

The outer ends of these levers 42 carry notched pendants 43 in line with the sheet detectors 11. Each detector finger is pivotally mounted on an arm 44 pivoted to a fixed support as at 45 and connected at its outer end by a link 46 to a lever 47 fixed to a rock shaft 48. The shaft 48 is continuously oscillated by a cam 49 acting through a cam follower 50 mounted on a lever 51 which in turn is connected with the shaft 48 through a link 52 and a lever 53.

The cam 49 is mounted on the shaft 14 of

the feed cylinder and has a concentric "high" extending about substantially the entire circumference of the cam with a relatively short depression 55 which aligns with the cam follower 50 in time to cause the detector finger to descend and feel for a sheet just as it is being presented to the front guide of the machine. A compression spring 51' acting against the lever 51 causes the cam roller 50 to follow the cam and reciprocates the shaft 48 as called for by the cam.

If the sheet being presented to the front guide is in all respects proper the detector fingers will be engaged by the leading edge of the sheet and swung out of their normal positions to disalign their upper ends from the notches in the pendants 43. Hence, when the detector fingers are lifted by the oscillation of the shaft 48 they will have no effect upon the cross shaft 39 and the latch 22 will be left engaged.

However, if the sheet presented to the front guide is defective as would be the case if the front edge were turned over at one side, at least one of the detector fingers would not be moved out of alignment with the notch in its associated pendant 43 and consequently the elevation of that detector finger would result in counter-clockwise oscillation of the cross shaft 39.

Such oscillation of the cross shaft 39, as noted hereinbefore, effects disengagement of the latch 22 with the result that the gripper opening cams drop down out of their operative positions so that the defective sheet, which would be carried along by the feed cylinder, would not be transferred to the impression or varnish cylinder. Instead the defective sheet would be carried around to the point at which the grippers of the feed cylinder are tumbled to their open positions; whereupon the sheet would be released for passage to the discard pile.

With the next revolution of the feed cylinder the gripper opening cams would be restored to their normal operative positions and the latch 22 reengaged. This is accomplished by a resetting cam 56 also revolving with the feed cylinder and in line with a cam follower 57 on the lower end of the medially pivoted lever 30. The lever 39 being connected to the horizontal bar 29 pulls the same back against the compression of the spring 32 as the resetting cam 56 passes under the cam following roller 57 to reengage the latch 22 and restore the cam supports 20 and 21 to their positions holding the gripper opening cams operative.

Concomitantly with the release of the gripper opening cams 18 and 19 to release the latch 22 in the manner described, the varnish roll 6 is caused to retract away from the surface of the impression or varnish cylinder so as to preclude the application of varnish to the cylinder during the time it travels without carrying a sheet.

Although the varnish roll or applicator involves considerable structure through which various improvements are achieved, for an understanding of the way in which release of the latch 22 effects retraction of the varnish roll it is sufficient to note that the roll and its associated structure are supported by a lever 58 pivoted as at 59 to a fixed support and in turn supported against dropping by a bell crank lever 60.

The bell crank lever 60 is fixed to a cross shaft 61 which extends across the entire machine, and one arm of the bell crank lever carries a roller 62 and the other arm has a stub shaft 63 projecting therefrom. The roller 62 engages the finished surface of a pad 64 on the underside of the lever

58, and the stub shaft 63 is engaged by a latch bar 65 and reset bar 66.

It is, of course, to be appreciated that there are two levers 58, one at each side of the machine and that there are likewise two supporting bell crank levers 60; but on the gear side of the machine, the lever 60 does not carry a stub shaft 63. Instead, it provides a spring abutment 67 against which the pressure of a spring 68 is applied. The spring 68 thus tends to rock the cross shaft 61 in the direction urging the stub shaft 63 against the latch bar 65. Consequently, if the latch bar 65 is moved out of engagement with the stub shaft 63 the cross shaft 61 rocks and the support for the levers 58 moves down a distance sufficient to disengage the varnish roll 6 from the impression or varnish cylinder.

The extent to which the cross shaft 61 rocks upon withdrawal of the latch bar 65 is defined by an adjustable stop 69 on each side of the machine.

The latch bar 65 has a fixed pivotal support 70 and is connected by means of a link 71 to a lever 72 fixed to the shaft 24. Thus, when the shaft 24 rocks in response to release of the latch 22 the latch bar 65 is lifted out of engagement with the stub shaft 63 with the result that the varnish roll is retracted concomitantly with the swinging of the cams 18 and 19 to their inoperative positions.

Restoration of the varnish roll to its operative position and reengagement of the latch bar 65 with the stub shaft 63 is effected by reciprocation of the reset bar 66. The free end of this bar is supported on a roller 73 to be at all times in line with the stub shaft 63, and its opposite end is connected as at 74 to a medially pivoted lever 75 which carries a cam follower 76 to track on a reset cam 77. The reset cam 77, which like the other reset cams is mounted on the shaft 14 of the feed cylinder, is timed to operatively actuate the reset bar when the opening in the impression or varnish cylinder in which the grippers are located is opposite the varnish roll.

Consequently, the momentary positive lifting of the varnish roll once each cycle the machine runs without a sheet on the impression or varnish cylinder will have no objectionable effect as the varnish roll will not contact the naked cylinder.

To enable the latch, which consists of the bar 65 and the stub shaft 63, to be accurately set, a set screw 78 is carried by the outer free end of the latch bar in position to have the head thereof engage against the stub shaft.

The varnish applicator assembly in itself embodies several important features. At the outset it is seen that this entire assembly is arranged to be moved or slid to and from its operative position which in itself is highly advantageous due to the accessibility it affords.

For this purpose the applicator assembly is slidably supported on tracks 79 fixed to and projecting from the side frames 13 of the machine. These tracks, which are U-shaped in cross section, provide slideways for supporting rails 80 on the outer ends of which the side frames 81 of the applicator assembly are secured.

Movement of the applicator assembly to and from its operative position is effected by rocking a shaft 82 by means of a crank 83 fixed to one end of the shaft. Also fixed on the crank shaft are two crank arms 84 the free ends of which are connected by links 85 to the side frames 81 of the applicator assembly. Thus, by swinging the crank 83 the assembly is quickly moved to

and from its operative position, and when moved out to its inoperative position shown in Figure 8, an electric drive motor 86 conveniently mounted on one of the side frames of the machine is automatically drivingly connected with the applicator assembly through the tensioning of a belt 87.

Thus, when the applicator assembly is racked back the liquid varnish may be kept agitated without necessitating the running of the entire machine.

The fountain or pot 88 which contains the liquid varnish is mounted between the side frames 84 to which it is rigidly secured, and extending across the top thereof with its axis fixed with relation thereto is a metal gauge roll 89. The ends of the shaft which mounts the gauge roll project beyond the side frames, and on the gear side of the machine, shown in Figure 8, this shaft carries a pulley 90 over which the belt 87 is trained and a drive gear 91 which meshes with a drive pinion 92 when the applicator assembly is in its operative position shown in light broken lines in Figure 8.

The drive pinion 92 is so mounted as to accommodate possible improper meshing with the gear 91, and to automatically bring these gears into proper mesh as the machine begins to operate.

The end portions of the gauge roll shaft provide the fixed supports for the levers 58 and also have supporting arms 93 pivotally mounted thereon. These arms 93 lie between the side frames 84 and the levers 58 and their free ends are connected by a cross shaft 94.

The cross shaft 94 pivotally supports another set of lever arms 95, the free ends of which carry bearings 96 in which the shaft ends of the rubber varnish roll 6 are journaled.

An eccentric adjusting bushing 97 mounted in each of the lever arms 95 and fitted onto the shaft ends 94 provides an adjustment for accurately setting the pressure with which the rubber roll 6 engages the gauge roll 89, and thereby determines the thickness of the varnish film applied to the work. Adjusting screws 98 provide means for turning the eccentric bushings, as will be readily apparent.

When the varnish roll 6 is in its operative position contacting the gauge roll and capable of applying varnish to the sheets carried by the impression or varnish cylinder, the outer ends of the lever arms 95, which carry the varnish roll, are supported on rests 99 fixed to the supporting arms 93. The varnish roll is thus arranged to swing about the axis of the gauge roll and its position of elevation with relation to the impression cylinder is dependent upon the position of the supporting arms 93.

These arms 93 in turn are adjustably supported on the levers 58, the adjustment being effected by screws 100 carried by the levers 58 and engaging portions of the supporting arms 93. Through this latter adjustment the operative position of the varnish roll 6 with respect to the varnish cylinder 5 is properly set.

When the latch bar 65 is disengaged from the stub shaft 63, allowing the bell crank lever 60 to swing in a counterclockwise direction, the leverage system supporting the varnish roll 6 is allowed to drop down to the position shown in Figure 4, in which the varnish roll is spaced from the impression cylinder and the printing couple is open.

The varnish roll is positively driven to revolve in the same direction as the varnish cylinder, but at a speed slightly different from that of the

varnish cylinder to effect a wiping action by means of a sprocket chain 101 trained about a sprocket 102 fixed to the varnish roll shaft, a sprocket on the shaft of the gauge roll, which is the driven roll, and an idler sprocket 103.

When the entire varnish applicator assembly is racked back or moved to its inoperative position shown in Figure 8, the varnish roll 6 may be swung up into plain view as clearly shown in Figure 7. This not only exposes the entire varnish fountain to view so that it can be readily cleaned out if necessary, but so holds the bearings 96 of the varnish roll that the roll can be easily removed. The position shown in Figure 7 to which the varnish roll is swung is defined by a stop link 104.

In the varnishing of printed sheets it is necessary to provide means for leaving parts of the sheets unvarnished, that is, dry strips must be left at intervals along the width of the sheets. For this purpose wipers 105 are provided. These wipers wipe the varnish off the rubber varnish roll so that in the finished work an unvarnished strip will appear in line with each such wiper.

Inasmuch as the location of the unvarnished or dry strips is dependent upon the nature of the work, the wipers are adjustable lengthwise of the varnish roll and to this end they are all mounted on a bar or track 106 fixed to the undersurface of the fountain and extending for the length thereof.

Each wiper has a mounting bracket 107 slideable along the length of the bar or track and adapted to be secured in any position along the length thereof by a set screw 108.

Medially pivoted to the bracket is a lever arm 109, the upper end of which has the wiper arm per se pivoted thereto and the lower end of which is arranged to abut against an adjustable stop 110.

A toggle 111 yieldingly urges the wiper down to its operative position defined by the engagement of the undersurface thereof with the adjacent top edge of the fountain, or holds the wiper in an upwardly swung position shown in Figure 7. With the wiper in its operative position, adjustment of the screw 110 moves the same toward and from the rubber varnish roll, as will be readily apparent.

It is to be observed that this manner of mounting the wipers and particularly the toggle arrangement, permits the wipers to be automatically swung to inoperative positions as the rubber varnish roll is lifted, and that when swung to such positions the toggles hold the same elevated so that the varnish roll can be returned to its operative position without interference from the wipers.

If, after the varnish roll is returned to its operative position, the wipers are not individually restored to their positions engaging the roll, the return of the varnish applicator assembly to its operative position automatically brings the wipers back into engagement with the varnish roll. This is accomplished by a guard 112 carried by the fixed part of the machine and provided with an overhanging arm which engages the raised wipers as the applicator assembly is moved into its operative position.

From the foregoing description, taken in connection with the accompanying drawings, it will be readily apparent to those skilled in the art that this invention provides means operable without stopping the press for opening the printing couple, i. e. retracting the varnish applicator roll

from the varnish cylinder upon presentation of a defective sheet at the front guides so as to preclude the application of varnish to the varnish cylinder, which continues to run "naked"; and that this invention also provides a simple manner of keeping the varnish in the fountain of a varnisher agitated when the machine is idle and without necessitating running the entire machine and that the entire varnish applicator assembly may be moved to a position making all parts thereof readily accessible.

What we claim as our invention is:

1. In a varnisher having a main frame and a varnish cylinder: a varnish applicator assembly including a varnish roll cooperable with the varnish cylinder; means on the main frame mounting the applicator assembly for movement to and from its operative position at which the varnish roll coats with the varnish cylinder; a main drive for the machine having means connectible with the applicator assembly to drive the same when said assembly is in its operative position; an auxiliary drive motor mounted to be nearer the applicator assembly in the operative position thereof than when said assembly is in its inoperative position; and a transmission belt for connecting the auxiliary drive motor with the applicator assembly to drive the same when said belt is taut, said belt being of a length such that when the applicator assembly is in its operative position the belt is loose and when the applicator assembly is moved out to its inoperative position the belt is taut.

2. In a varnisher having a main frame and a varnish cylinder mounted thereon: substantially horizontal slideways carried by the main frame; an applicator assembly including a varnish roll cooperable with the varnish cylinder in the operative position of the applicator assembly; means mounting the applicator assembly on said slideways for movement to and from its operative position; a main drive for the machine having power take-off means connectible with the applicator assembly to drive the same when said assembly is in its operative position; a driven pulley on the applicator assembly; an auxiliary drive pulley on the main frame of the machine so positioned that the distance between said pulleys is less when the applicator assembly is in its operative position than when it is in its inoperative position; and a transmission belt connecting the drive pulley with the driven pulley and adapted to be automatically tightened upon moving the applicator to its inoperative position so that the applicator may be run from the drive pulley when in its inoperative position.

3. In a varnisher having a main frame and a varnish cylinder mounted thereon: substantially horizontal slideways carried by the main frame; an applicator assembly including a varnish roll cooperable with the varnish cylinder in the operative position of the applicator assembly; means mounting the applicator assembly on said slideways for movement between an operative position at which its varnish roll is in operative relation with the varnish cylinder and an inoperative position at which the varnish roll is spaced from the varnish cylinder; a main drive for the machine; disconnectible means for driving the applicator assembly from the main drive of the machine when the applicator assembly is in its operative position; a pulley on the applicator assembly drivably connected with the varnish roll; an auxiliary drive motor on the main frame of the machine for driving the applicator assem-

bly in its inoperative position and so positioned that the distance between the drive motor and said pulley is less when the applicator assembly is in its operative position than when it is in its inoperative position; and a transmission belt connecting the drive motor with said pulley and adapted to be automatically tightened upon moving the applicator to its inoperative position to thereby drivingly connect the applicator with the auxiliary drive motor.

4. In a varnisher, a varnish applicator assembly comprising: a varnish fountain; a varnish applicator roll; pivoted lever arms mounting the varnish applicator roll for movement from an operative position having a portion thereof disposed within the fountain to an inoperative position lifted entirely out of the fountain; a gauge roll revolvable on a fixed axis and cooperable with the applicator roll; and adjustable pivots for the lever arms; said pivots having adjustable means for varying the position of the axis of pivotal movement of said lever arms whereby the position of the varnish applicator roll may be adjusted to thus adjust the pressure with which the same is engaged by the gauge roll.

5. In a varnisher having a varnish cylinder, a varnish applicator assembly comprising: an open topped fountain; a varnish applicator roll for transferring varnish from the fountain to work carried on the varnish cylinder; means for detecting a faulty sheet presented to the machine, and means mounting said varnish applicator roll for rotation and for bodily movement away from the varnish cylinder to preclude the application of varnish thereto when the cylinder is running naked comprising a pair of supporting lever arms pivoted to swing about a fixed axis spaced from the axis of rotation of the varnish applicator roll, a movable support for said lever arms, and means including latch mechanism actuated by said detector means for releasably retaining said movable support in its operative position.

6. In a printing machine having cooperating rotary elements constituting a printing couple: supporting means mounting one of said rotary elements for rotation and for bodily movement toward and from the other rotary element, said supporting means being biased to hold its rotary element away from the other element; means including latch means releasably holding said supporting means in a position in which the rotary elements are in cooperative work performing juxtaposition; detector means for detecting a faulty or misaligned sheet presented to the machine; means connecting said detector means with said latch means and operable to trip the latch means in consequence to detection of a faulty or misaligned sheet by the detector means to thereby permit said supporting means to carry said one rotary element away from the other rotary element in response to said bias; and means for cyclically moving said supporting means back to operative position against said bias after it has been so released and for resetting the latch means.

7. In a varnisher having a varnish cylinder and a varnish applicator roll: a pair of arms rotatably supporting the varnish applicator roll, said arms being pivoted on an axis spaced from the axis of the varnish cylinder and parallel thereto; means including latch means releasably holding said arms in an operative position in which the applicator roll is held in juxtaposition to the varnish cylinder; detector means for detecting a faulty or misaligned sheet presented to the machine; means connecting said detector means

11

with said latch means whereby the latch means is tripped in consequence to detection of a faulty or misaligned sheet by said detector means to thereby release said pair of arms to permit them to carry the varnish applicator roll away from the varnish cylinder; and means for cyclically moving said supporting arms back to operative position and resetting the latch means.

8. In a machine of the type having a printing couple comprising cooperating rotary elements one of which is an impression cylinder having a gripper pocket and grippers operating therein to hold a sheet to the impression cylinder; means for feeding sheets to the impression cylinder; detector means for detecting defective sheets as they are presented to the machine; means under the control of said detector means for effecting opening of the printing couple upon the presentation of a defective sheet to said detector means; and means including a cyclically operable motion producing member driven in timed relation with the impression cylinder for reclosing the printing couple when the other rotary element is opposite the gripper pocket in the impression cylinder so that if the next successive sheet presented to the machine is also defective momentary reclosure of the printing couple will not result in contacting engagement between the rotary elements at a time when the impression cylinder is running naked.

9. In a varnisher having a frame and a varnish cylinder mounted in the frame: a varnish applicator assembly including a fountain and an applicator roll; means mounting the applicator assembly for movement with respect to the frame to an operative position in which the applicator roll coacts with the varnish cylinder and is immersed in varnish contained within the fountain, or to an inoperative position in which the applicator roll is removed from the varnish cylinder and is adapted to be lifted to an elevated position entirely out of the fountain; a wiper for wiping varnish from the applicator roll; means mounting said wiper including a spring toggle adapted to hold the wiper in its wiping position coacting with the varnish applicator roll or in a position entirely clear of the roll permitting the roll to be lifted to its elevated position; and a part on the frame in a position to engage the wiper and push it to its wiping position in the event the applicator assembly is returned to its operative position while the wiper is in its inoperative position.

10. In a printing machine the combination of: a printing couple comprising complementary rotary elements biased apart; a latch normally holding said elements together; means for feeding sheets to the couple; detector means for detecting defective sheets as they are presented to the machine; means under the control of said detector means for tripping said latch to thereby effect opening of the printing couple upon the presentation of a defective sheet to said detector means; and cyclically operable means for effecting reclosure of the printing couple and resetting of the latch in the event the printing couple has been opened whereby the opening and reclosing of the printing couple takes place without stopping the machine.

11. A machine of the type having a printing couple comprising complementary rotary elements biased apart and latch held together, detecting means for detecting a defective sheet presented to the machine, and means responsive to the functioning of said detecting means for

12

releasing the latch to permit the complementary rotary elements to separate upon the presentation of a defective sheet to the machine, characterized by: cyclically operable means for automatically bringing said rotary elements together and for resetting of the latch after each separation of said rotary elements whereby the opening and reclosing of the printing couple takes place automatically without stopping the machine.

12. In a machine of the character described: a printing couple comprising complementary rotary elements biased together, one of said elements being an impression cylinder having a gripper pocket and grippers in said pocket to hold a sheet to the impression cylinder; a latch normally holding said elements together; means for feeding sheets to the printing couple; detector means for detecting defective sheets as they are presented to the machine; latch actuating mechanism under the control of said detector means for tripping the latch to thereby effect opening of the printing couple upon the presentation of a defective sheet to said detector means; and cyclically operable means for automatically reclosing the printing couple and resetting the latch, said cyclically operable means being so timed with rotation of the impression cylinder that reclosure of the printing couple occurs when the other element of the printing couple is opposite the gripper pocket in the impression cylinder so that if the next successive sheet presented to the machine is also defective the momentary reclosure of the printing couple will not effect contacting engagement between the elements thereof.
13. In a machine of the character described: cooperating rotary elements providing a normally closed printing couple, one of said elements being bodily movable with respect to the other and biased to a position in which the printing couple is open; latch means holding said element in the closed position; detector means responsive to the presentation of a defective or misaligned sheet to the machine; latch actuating means operable by the detector means upon the presentation of a defective or misaligned sheet to the machine for tripping said latch means to thereby effect opening of the couple; and means including a cam rotating in timed relation with one of said elements of the printing couple for cyclically moving said bodily movable printing couple element back to the closed position after the printing couple has been opened and for resetting the latch means.
14. In a varnisher, a varnish applicator assembly comprising: a varnish fountain; a varnish applicator roll adapted to dip into varnish within the varnish fountain when in operative position; a gauge roll revolvable on a fixed axis and cooperable with the applicator roll; lever arms mounting the varnish applicator roll for movement from an operative position riding on the gauge roll to an inoperative position spaced therefrom; and adjustable pivots for the lever arms including eccentric bushings mounted in said lever arms whereby the position of the varnish applicator roll may be adjusted to thus vary the pressure with which the same engages the gauge roll and thereby regulate the thickness of the varnish being applied by the applicator.
